UNITED STATES PATENT OFFICE

2,125,065

ELECTRIC LIGHT FIXTURE

Harmon J. Cook, Torrington, and George E. Fitzgerald, Bridgeport, Conn., assignors to The Connecticut Electric Manufacturing Co., Bantam, Conn., a corporation of Connecticut

Application May 23, 1935, Serial No. 22,994

9 Claims. (Cl. 173—336)

This invention relates to electric light fixtures, and more particularly to a switch socket provided with a pair of side taps and having insulating guide blocks held in place by the casing thereof for directing the prongs of outlet plugs into engagement with said taps.

One object of this invention is to provide a socket of the above nature in which the insulating guide blocks are held detachably in position by the outer shell casing, and are not connected to the interior switch and contact carrying body in any way.

A further object is to provide a double tap pull chain socket of the above nature which is approximately the same size as the standard pull chain sockets, so that it may be readily substituted therefor whenever desired.

A still further object is to provide a side tap socket of the above nature in which the interior body is removable from the casing without disturbing the side insulating guide blocks.

A further object is to provide a double-tap socket of the above nature in which the tap contacts are double ended and pass transversely through the interior insulating body in alignment with side slots provided in the insulating guide blocks of the casing.

A further object is to provide a double-tap outlet socket which will be simple in construction, easy to assemble, inexpensive to manufacture, compact, and very durable in use.

With these and other objects in view, there has been illustrated on the accompanying drawing one form in which the invention may be conveniently embodied in practice.

In the drawing:

Fig. 1 represents a side elevation of the improved pull chain socket to which a pair of side outlet taps have been applied.

Fig. 2 is a vertical sectional view on an enlarged scale taken along the line 2—2 of Fig. 1, looking in the direction of the arrows.

Fig. 3 is a side elevation of the interior body as it appears when removed from the casing.

Fig. 4 is a side elevation of the same, similar to Fig. 3, but taken from the opposite side thereof.

Fig. 5 is a transverse sectional view of the electric socket, taken along the line 5—5 of Fig. 2, looking downwardly.

Fig. 6 is a front perspective view of one of the insulating guide blocks.

Fig. 7 is a rear perspective view of the same.

Fig. 8 is a diagrammatic view of the electric circuit.

Referring now to the drawing in which like reference numerals denote corresponding parts throughout the several views, the numeral 10 indicates an outside shell or casing, preferably of metal, to which a top cap 11, also preferably of metal, may be attached by snapping thereupon in the usual well-known manner. The apex of the cap 11 is provided with a tapped bushing 12 by means of which an electric fixture may be attached to a threaded conduit pipe 13 for housing a two-wire conductor cord, not shown.

The bottom of the shell 10 is provided with the usual shade-holder-engaging threaded section 14, and the intermediate section of said shell has a pair of opposed side openings 15 each having a curved top portion and a rectangular base for detachably receiving a pair of insulating guide blocks 16 and 17, which fit into the openings 15 and are retained within the shell by the flanges 23 and 24 thereof. The blocks 16 and 17 are each provided with a pair of parallel narrow rectangular passages 18 and 19 depressed inwardly from the outer face of said blocks and connected therewith by ornamental countersunk faces 20 and 21 which assist in guiding the prongs of a plug (not shown) into said slots 18 and 19.

In order to retain the blocks 16 and 17 in the shell 10 without any connection with the interior body or mechanism, said blocks are each provided with rearwardly extending side wings 22 having lateral flanges 23 at their extremities which are adapted to engage the inside of the casing 10 beyond the side edges of the openings 15.

The upper convex sections of the guide blocks 16 and 17 are provided with upstanding flanges 24, which engage behind the shell and cooperate with the flanges 23 to hold said blocks in the shell. The blocks 16 and 17 are each provided on their interior lower edges with small angular recesses 25 for engaging with curved lugs 26 extending inwardly from the shell at the lower edge of the openings 15 thereof.

The casing 10 is provided with the usual insulating sleeve 27 and the cap 11 has an insulating insert 28 to electrically and mechanically shield the interior parts from the metal of the shell 10 and cap 11 respectively.

The interior body of the device is generally indicated by the numeral 29 and comprises a pair of split sections 30 and 31, preferably made of porcelain or other molded insulating material. The split sections 30 and 31 are so configurated as to accommodate the necessary electric contacts and connecting elements as clearly

illustrated in the drawing. The two split sections 30 and 31 of the interior body are adapted to be held together by a single bolt 32 and associated nut 33 located in the upper right-hand corner of the body, as viewed in Fig. 3.

A threaded socket shell contact 34 is attached to the lower end of the insulating body 30, 31, as by a pair of bolts 35 and 36, the bolt 35 being shorter than the bolt 36 and provided with a nut 37, which is seated in a cross-shaped socket 38, the cross section of said socket being adapted to prevent the nut 37 from turning.

The longer screw 36 is received in a vertical slot 39 provided in the opposite side split section 31, and threadedly engages an inturned tapped end 40 at the lower end of an angular terminal conductor strip 41. The upper end of the strip 41 is provided with a binding screw 42 to which one of the insulated wires 43 of the two-wire conductor cord may be attached as shown.

The bases of the split sections 30, 31 are jointly formed with the usual depending projection 44 adapted to fit within a locating aperture provided in the upper end base of the socket shell contact 34. A resilient convex center contact 45 is positioned adjacent the projection 44 and has a reduced connector strip 45a extending upwardly through a narrow slot 46 formed by opposed grooves on the adjacent faces of the split sections 30, 31. The upper end of said strip terminates in an interior chamber 47 where it is electrically connected with a socket switch mechanism 48 located in said chamber 47. The switch mechanism 48 is preferably of the conventional oscillating disc advancing ratchet type and is mounted upon a rod 49 transversely mounted in the split sections 30 and 31. A pull chain 50 is connected to a hook 50a on a spring 51 actuated insulating toothed disc 50b, the teeth of which are adapted to engage in succession the teeth of an advancing ratchet 51.

In order to connect the switch mechanism 48 to the electric circuit, the other conductor 52 leads to an angular strip 53 located outside the split section 30, and is held securely thereto and also connected to the switch mechanism 48 by means of a tubular eyelet 54. The upper offset end of the strip 53 is provided with a binding screw 55 to which the conductor wire 52 may be connected.

The lower end of the angular strip 53 is connected with a double ended outlet tap contact 56 transversely located in a horizontal socket 57 positioned in alignment with one set of the openings 18 and 19 of the guide blocks 16 and 17 and passing entirely through the split plug sections 30, 31. The opposite ends of the double-ended contact 56 are provided with inturned resilient tongues 58 and 59 by means of which an electrical contact is made with the prongs of any conventional push plug, not shown.

The other double end tap contact 60 is arranged in a similar manner within a transverse horizontal socket 57a and is connected to the electric circuit by means of a short auxiliary conductor strip 61 passing upwardly through a side slot 62 formed on the outside of the plug section 31, and is electrically connected with the inturned end 40 of the vertical conductor strip 41 leading to the body part 42.

Operation

To connect the fixture to the electric supply circuit it will only be necessary to remove the

cap 11 from the shell 10, in the usual manner. The interior body 29 may then be pulled out without interfering with the guide blocks 16 and 17. The conductor wires 43 and 52 may then be connected to the binding screws 42 and 55. The body 29 may then be reinserted into the casing shell 10 and the cap 11 snapped back into position.

It will be understood that the guide blocks 16 and 17 will be assembled in the apertures 15 from the interior of the casing 10 before the body 29 has been inserted. The recesses 25 will first be fitted over the lugs 26, after which the upper ends of the guide blocks 16 and 17 will be forced outwardly into the curved upper sections of the apertures 15.

It is to be noted from the above construction that the double-end tap contacts 53 and 60 will be constantly energized whether the switch mechanism 48 is in open or closed position, so that one or more double-prong plugs may be inserted into the side taps and will draw current therefrom irrespective of whether the socket switch 48 is in the "on" or "off" position.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an electric fixture, a casing, a removable interior insulating body located in said casing, said body having a side outlet tap, said casing having a side aperture in alignment with said tap, an insulating guide block having a portion fitting in and projecting out through said aperture and having laterally extending means inside said casing to retain said block in said casing, said body being unconnected with and freely removable from said casing without disturbing said block.

2. In an electric fixture, a casing, a removable interior insulating body located in said casing, said body having a double-contact side outlet tap, said casing having a side aperture in alignment with said tap, an insulating flanged guide block projecting out through said aperture and held in place in said casing, said body being removable from said casing without disturbing said block, said block having a pair of slots for guiding the prongs of a double prong plug into engagement with the contacts of said tap, the flanges on said guide block serving to hold said slots in alignment with said tap and preventing said block from falling out through said aperture.

3. In a lamp socket, an interior insulating body, a pair of conductors in said body having a connection to a source of current, an end socket for an electrical device, a side outlet tap having a pair of contacts connected with said conductors, a casing freely slidable upon and unconnected with said body and having a side aperture in alignment with said tap, and an insulating guide block projecting into said aperture adapted to receive the prongs of a double prong-plug and guide them into engagement with the contacts of said side outlet tap, said block having an interior flange to hold it within said casing.

4. In an electrical fixture, a casing, an interior body member of insulating material having a side outlet tap, said casing having a side aperture in alignment with said side outlet tap and an insulating guide block detachably fitted into said aperture, said block having interior flanges to prevent it from being forced outwardly through said aperture when the body member is in position within said casing, said body member being removable longitudinally from said casing without disturbing said block. 5
5. In an electrical fixture, a casing, an interior body member of insulating material having a side aperture in alignment with said tap, an anchor fulcrum lug integral with said casing extending inwardly from the edge of the lower part of said aperture, and an insulating guide block unconnected with said casing fitted into said aperture 10 and having a recess embracing said lug to hold said block in alignment with said tap, said body member being freely removable from said casing without disturbing said block. 15
6. In an electric fixture, a casing, an insulating body slidably fitting the interior of said casing, a socket mounted on one end of said body, said body having a pair of side current taps, a pair of conductor straps connecting the terminals of said socket and side taps in parallel, a pair of double-ended tap outlet contacts connected to said straps, and a pair of insulating guide blocks extending outwardly through said casing and serving to direct the prongs of a pair of push-plugs into engagement with the contacts of said side current taps, said body being removable from said casing without disturbing said blocks. 20
7. In an electric fixture, a casing having a pair of side apertures, an insulating body slidably fitted into the interior of said casing and having 25
- a pair of transverse slots extending therethrough, a pair of double-ended contacts located in said slots, means to connect said contacts with the two terminals of a source of current, and a pair of insulating guide blocks extending outwardly through and carried by said casing to direct the prongs of a pair of electric push-plugs into engagement with said double-ended contacts, said body being removable from said casing without disturbing said blocks. 30
8. In an electric fixture, a casing having a pair of side apertures, an insulating body slidably fitted into the interior of said casing and unconnected therewith, a switch-controlled lamp socket mounted on one end of said body, said body having a pair of transverse slots extending therethrough, a pair of plug tap contacts located in said slots, and means to connect the terminals of said lamp socket and said tap contacts in parallel whereby a double prong plug may draw current from said tap contacts, a plug prong guide block in each side aperture of said casing, said body and tap contacts being unconnected with and freely removable from said casing without interfering with either of the plug prong guide blocks by a longitudinal sliding movement. 35
9. In an electrical fixture, a cylindrical casing having a side aperture, an insulating block having slots therethrough disposed in said aperture and having a flanged portion within said casing underlying the edges of the aperture therein, and an insulating body carrying contacts and being freely slidable longitudinally into said casing to a position between said block and the opposite side of said casing to align the contacts with the slots in said block, said body being unconnected with said casing. 40
